(57) CLAIM

The ornamental design for a tray for food products, as shown and described.

DESCRIPTION

FIG. 1 is a perspective view of a tray for food products according to my new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines showing of the rim, medial section and lugs of the design are for illustrative purposes only and form no part of the claimed design of FIGS. 1-7.
